LOOM

Linden Morgan Valentine, Pelham, N. Y.

Application August 2, 1940, Serial No. 349,723

9 Claims. (Cl. 139—13)

This invention relates to the art of textile manufacture and more particularly to loom construction and shuttle manipulation of the general nature as but improvement over my prior Patent Number 2,144,947, of January 24, 1939, with specific application to circular looms.

The objects of the invention are to provide an improved circular loom wherein a multiple transition of shuttles around the loom may be simultaneously in operation; to positively and continuously feed the shuttles around the loom all at the same speed at the same time; to provide for multiple and continuously progressive shedding of the warp threads in synchronism with advancement of the respective shuttles in each shed; to provide a circular loom which will permit laying of a plurality of weft threads at one time and at short intervals around the loom; to actuate the several shuttles in their circular orbit with greater rapidity than heretofore possible; to enable a sturdy, effective and readily accessible assembly of parts to be employed for actuating the shuttles and for actuating the heddles; to utilize the shuttle supporting means or reeds also for guiding and actuating purposes; to secure simplicity of construction and operation; and to obtain other advantages and results as may be brought out in the following description.

Referring to the several accompanying drawings in which like numerals of reference indicate similar parts throughout the several views:

Figure 1 is an elevation of a circular loom embodying my invention, looking at the same from a side, which for convenience, will be termed the front;

Figure 2 is a plan of the same;

Figure 3 is a vertical central sectional view drawn to larger scale than Figure 1 and broken away substantially at the vertical center;

Figure 4 is a perspective view of a portion of the vertically grooved drum;

Figure 4a is a similar perspective view, but showing a modified construction of drum and cams;

Figure 5 is a detail plan of a portion of the heddle cams and associated parts;

Figure 6 is a plan of the shuttle supporting and operating means;

Figure 7 is a diagrammatic or developed elevational view illustrating the forward movement of the shuttles and the corresponding relationship of the shuttles and reeds or actuating members;

Figure 8 is a similar view on increased scale 55

over Figure 7 and showing the tail end of a shuttle and reeds effective therewith;

Figure 9 is a horizontal section on line 9—9 of Fig. 8;

Figure 10 is an elevation of one of the supporting reeds, and

Figure 11 is a similar elevation of one of the upper reeds.

In the specific embodiment of the invention illustrated in said drawings, the loom comprises in general a lower portion wherein are situated a circular series of horizontally disposed and radiating heddles. Above this lower portion in axial alignment therewith but of considerably smaller diameter are the reed-supporting and reed-operating means. The warp threads feed upwardly and the fabric is formed at the outside of said reed-supporting and reed-operating means as a tube. Description will first be made of the lower or heddle portion of the machine.

The heddle portion of the machine comprises four concentric rings situated about a common vertical axis. There is considerable distance radially between each successive ring. The innermost ring 20 and the outermost ring 21 are each rotatable, whereas the other two rings 22 and 23 are fixed. Any suitable supports 24 may be provided to support the rotatable rings, said supports being here shown as having socketed upper ends for receiving the lower edges of said rings therein. Other supports 25 are provided to receive and support the fixed rings 22 and 23.

It will be observed that the several rings 20, 21, 22 and 23 are cylindrical so as to be upstanding on their lower edges. Each fixed ring supports a pair of horizontally disposed fixed annular plates; thus from the inner one 22 of the intermediate fixed rings extend an upper fixed plate 26 and a lower fixed plate 27, and from the outer one 23 of the intermediate fixed rings extend an upper fixed plate 28 and a lower fixed plate 29. The respective upper fixed plates 26 and 28 are in a common plane, whereas the respective lower fixed plates 27 and 29 are in a common plane at a distance below the plane of the upper fixed plates. Furthermore, the fixed plates 26 and 27 from the inner fixed ring extend in a direction inwardly therefrom to adjacent the innermost rotatable ring 20, whereas the fixed plates 28 and 29 from the outer fixed ring extend in a direction outwardly therefrom to adjacent the outermost rotatable ring 21. Appropriate ledges are formed on or attached to the fixed rings for supporting the fixed plates next a peripheral margin thereof. Screws or other

suitable means are preferably used to secure the plates to the ledges. The upper face of each of the horizontally disposed fixed plates has evenly spaced radially extending grooves throughout. The grooves are situated and related so that each groove of one plate is aligned with a corresponding groove in the other plate in the plane therewith. Preferably the aligned grooves of the upper pair of plates are staggered with respect to the aligned grooves of the lower pair of plates. The grooves form guiding slideways for bar-like heddles end portions of which always remain in the grooves of aligned pairs of the grooves. Thus the midportion of the heddles are always spanning the space intervening between the fixed rings 21 and 23.

The heddles are each horizontally flattened for short lengths thereof, as at 31, and perforated therat to pass the warp threads slidably therethrough and enable the several warp threads to be swung back and forth for tenting the same as the heddles slide back and forth. Next the ends of the heddles as part thereof, are upstanding lugs 32 which are the only parts of the heddles which project above the grooved surface of the plates.

Immediately above the fixed plates 26, 27, 28 and 29 are rotatable cam plates 33, 34, 35 and 36 respectively which are annular and extend substantially from the rotatable ring to the nearest fixed ring. These cam plates have appropriate endless cam grooves therein receiving the lugs of the heddles therein. As the cam plates rotate, the cam grooves function to reciprocate the heddles successively and progressively tent the warp threads as a continuous operation. The cam plates as here shown are secured by screws or otherwise, to cam-supporting, annular plates 37, 38, 39 and 40 respectively, each flatwise of and immediately above its respective cam plate. Each cam plate and its supporting plate is in effect a unitary structure, being fabricated in parts and secured together as described as a manufacturing expedient. Appropriate ledges are formed on or attached to the upstanding rotatable rings 20 and 21 for supporting the cam plates and cam-supporting plates therefrom. Any suitable means, such as screws, attach the cam-supporting plates to their respective ledges, and thus the cam plates will rotate with the rotatable rings and obtain the sliding of heddles as above described. Said fixed rings are vertically slotted downwardly from their upper edges, as at 41, 42 respectively, to pass the heddles therethrough.

The innermost rotatable ring 20 has an annular rack 43 on its inner periphery with which meshes a pinion 44 by which the ring is actuated continuously in one direction. Likewise the outer rotatable ring 21 has an annular rack 45 on its outer periphery with which meshes a pinion 46 by which that ring is also actuated continuously in the same direction as the first. The gear ratio of the driving gears (not shown) is properly proportioned to cause both rotatable rings to make the same number of revolutions during operation.

Seated for support on the upper edge of the inner fixed ring 22 is an axially vertical reed cylinder 50. This cylinder in its preferred construction has vertical grooves 51 in its outer cylindrical surface and corresponding inner grooves 52 vertically on the cylindrical inner surface. Each groove for a lower portion thereof is slotted through, at 53, to the corresponding groove on

the other face of the cylinder. There are just as many grooves on the outer surface as on the inner surface and the grooves are directly opposed.

Outer reeds 54 are situated in and vertically slidable in the several outer grooves whereas inner reeds 55 are situated in and vertically slidable in the inner grooves. All said reeds have lateral portions extending therefrom at their lower ends each in a radial direction with respect to the cylinder and protruding outwardly from the cylinder. The lateral portions 56 of the outer reeds have their outer ends toed downward at 57 and are shorter than the lateral portions 58 of the inner reeds. The lateral portion 58 of each inner reed provides two upstanding ears 59, 59 thereon suitably spaced to accommodate the width dimension of a shuttle 60 therebetween. The lateral portions 58 of the several reeds 55 function to support the shuttle when thereover, and the said ears guide the shuttle in a circular orbit around the cylinder. The downwardly directed toes 57 of the lateral portions 56 of the outer reeds are substantially midway between and above the ears of the lower lateral portions 58 of the inner reeds so as to engage in a longitudinal depression at the top of the shuttle 60 next the ends thereof. The ends of the shuttle are rounded or otherwise tapered for enabling the portions of the reed engaging behind the shuttle to squeeze it forward. The squeezing action introduces a moment of force in a direction longitudinal of the shuttle which thereby supplies the forward actuation.

Fitting rotatably around said grooved cylinder for approximately the upper half thereof is an outer cylindrical cam 62 having an endless cam groove 63 therearound. The outer reeds 54 project under the said cam entirely within the vertical grooves 51 except for a lug 64 on each reed near the upper end thereof, said lug projecting outwardly into said cam groove 63. As the cam 62 rotates, the reeds will have longitudinal movement with respect to the cylinder in accordance with the displacement necessitated for the lug to follow the cam groove. Similarly an inner cylindrical cam 65 fits rotatably next the inner cylindrical surface of the grooved reed cylinder 50 and provides an endless cam groove 66 therearound. The inner reeds 55 project under said cam entirely within the vertical grooves except for a lug 67 on each reed near the upper end thereof. These lugs project into the cam groove 66 and thus, with the cam groove, control the movement of the reeds. The cam grooves are shaped to actuate the reeds to afford space for the several shuttles, to open a path for the shuttles as they advance, to squeeze the shuttles forward, and to beat the weft into the fell of the fabric.

For ease in manufacture, separate parts may be provided upon which to mount the cam cylinders. As here shown, an outer sleeve 68 is at the upper and outside part of the outer cam, with the parts of the cam screwed or otherwise attached thereto. Similarly the inner cam is mounted on a sleeve 69 at the inside of the cam. At the top of each sleeve is attached a rack 70, 71 each of which has been here shown as shouldered to slidably ride on a circular track 72 secured to the top of the grooved or reed cylinder 50. It will be remembered that the said reed cylinder is fixed, and so said track 72 is likewise fixed, but the racks, cam cylinders and sleeves are all rotatable and in use have a steady con-

tinuous rotation with both cams 62 and 65 making the same number of revolutions. Gears 73, 74 in mesh with racks 70, 71 and having proper ratio to give equal revolution of the cams, are carried upon and fixed to a cross-shaft 75 to operate the rotatable parts and thereby obtain sliding motion for the reeds. As indicated more especially in Figure 1, said shaft is connected through suitable driving parts to any appropriate source of power (not shown). It is to be understood that the drive for the heddle cams and drive for the reed cams are interconnected and synchronized.

If so desired, all of the reeds may be situated in grooves on the outer surface of the grooved cylinder. Such arrangement is shown in Figure 4a which shows grooved cylinder 50a vertically grooved at 51a on its outer surface only. Reeds 54 as heretofore described ride in every alternate groove 51a, said reeds having lateral outwardly projecting portions 56 and toed ends 57 as previously described. In the intervening grooves 51a ride reeds 55a very similar to previously described reeds 55. They provide lateral shuttle-supporting portions 58a and upstanding guiding ears 59 as before. But instead of passing through a slot in the reed cylinder, they are in outer grooves and are inserted under an outer cam cylinder 62a. This cam cylinder has one cam groove 66a to receive outwardly projecting lugs 67a on these shuttle-supporting reeds, and another cam groove 63a for receiving the lugs 64 of the previously described reeds 54. The modified structure necessarily reduces the possible number of reeds to one half of the possible number in the preferred construction. As many reeds as possible are preferred since they afford a better support and actuation for the shuttle and better beating of the weft into the fell.

In any event, a plurality of continuously progressing shuttles are provided for simultaneous operation, and between each shuttle the cam grooves cause the reeds to rise and carry the weft into the fell, the reeds overlying the shuttle passing inside the tubular-formed fabric 76 and the reeds by which the shuttles are supported functioning as the beaters. A loom such as shown having six shuttles will accordingly add six weft threads to the fell with each complete revolution of the cam cylinders and shuttles. It is also to be noted that the shuttles are always at a constant level, supported and actuated only by the reeds and situated at readily accessible positions to the operator.

I claim:

1. A circular loom comprising a longitudinally grooved cylinder, a plurality of shuttles having orbital paths of transition around the cylinder, a plurality of reeds one in each of said grooves and slidably longitudinally thereof, said reeds each having a lateral projection at one end extending outward from said cylinder for engagement with a passing shuttle, said reeds comprising two series of which the projections of one series are longer than the projections of the other series and underlie and cross entirely beneath the shuttle, and the projections of the other series are shorter than those of the first series and overlie and partly cross the shuttle, and means for sliding the reeds and squeezing the rear of the shuttles for advancing the shuttles simultaneously and continuously around the cylinder.

2. A circular loom comprising a longitudinally grooved cylinder, a plurality of shuttles having

orbital paths of transition around the cylinder and forming a tubular woven fabric surrounding the upper part of said cylinder, a plurality of reeds one in each of said grooves and slidably longitudinally thereof, said reeds each having a lateral projection at one end extending outward from said cylinder for engagement with a passing shuttle, part of said projections underlying and part overlying the shuttle, all of said projections being movable upwardly between shuttles transversely to the woven fabric as far as the fell of the fabric, and means for successively sliding reeds in engagement at the rear of the shuttles to lessen the space between the overlying and underlying projections and thereby squeezing the shuttles forwardly.

3. A circular loom comprising a longitudinally grooved cylinder, a plurality of shuttles having orbital paths of transition around the cylinder for weaving a tubular fabric therearound, a plurality of reeds one in each of said grooves and slidably longitudinally thereof, said reeds each having a lateral projection at one end extending outward from said cylinder for engagement with a passing shuttle, part of said projections underlying and part overlying the shuttle, means for sliding the reeds and squeezing the rear of the shuttles for advancing the shuttles simultaneously and continuously around the cylinder, and said means also elevating between shuttles the underlying reed projections with said projections continuously beneath and advancing the weft thread toward the woven fabric for beating the weft into the fell.

4. A circular loom comprising a longitudinally grooved cylinder, a plurality of shuttles having orbital paths of transition around the cylinder for weaving a tubular fabric therearound, a plurality of reeds one in each of said grooves and slidably longitudinally thereof, said reeds each having a lateral projection at one end extending outward from said cylinder for engagement with a passing shuttle, part of said projections underlying and part overlying the shuttle, the underlying reeds having upstanding ears for guiding the shuttles in their orbital paths the overlying projections being engageable with the shuttle and of a length less than the underlying projections and adapted to move upwardly within the formed tubular fabric, and means for squeezing the rear of the shuttles for actuating said shuttles simultaneously and continuously around the cylinder.

5. A circular loom comprising a cylinder longitudinally grooved inside and out, a shuttle having an orbital path around the cylinder, a set of reeds in the inside grooves and a set of reeds in the outside grooves, one set of said reeds having lateral extensions for underlying said shuttle and the other set having lateral extensions overlying said shuttle, and means for sliding said reeds and progressively squeezing the extensions of one set toward the extensions of the other set for advancing the shuttle therebetween.

6. A circular loom according to claim 5 wherein said means comprises a pair of cylindrical cams, one inside and one outside of the grooved cylinder.

7. A circular loom according to claim 5 wherein said means comprises a pair of cylindrical cams, one inside and one outside of the grooved cylinder, a circular rack on each cylindrical cam, and a gear in mesh with each rack and rotating said cylindrical cams with the same number of revolutions each.

8. A circular loom comprising a cylinder longi-

tudinally grooved on one of its cylindrical surfaces, a shuttle having an orbital path around the cylinder, two sets of reeds in said grooves every alternate reed having an extension therefrom underlying the shuttle and constituting one of said sets, and the intervening reeds constituting the other set and having extensions overlying said shuttle, extensions of said intervening set of reeds being shorter than the extensions of the alternate reeds for enabling the shorter extensions to pass the fell of the fabric and the

longer extensions to beat the fell into place in the fabric, and means for actuating reeds of one set toward reeds of the other set for squeezing and thereby advancing the shuttle.

5 9. A circular loom in accordance with claim 8 wherein the grooves are on the outside of the cylinder and wherein said means comprises a cam cylinder having two continuous cam grooves, one for actuating each set of reeds.

10
